UNITED STATES PATENT OFFICE.

ALFRED FISHER, OF CHICAGO, ILLINOIS.

MELTING-FURNACE.

1,258,666.

Specification of Letters Patent. Patented Mar. 12, 1918.

Application filed December 4, 1916. Serial No. 134,980.

To all whom it may concern:

Be it known that I, ALFRED FISHER, a citizen of the United States of America, and resident of Chicago, Cook county, Illinois, 5 have invented a certain new and useful Improvement in Melting-Furnaces, of which the following is a specification.

My invention relates to furnaces for melting brass or other metals, and it relates more 10 especially to furnaces of this kind in which the heat is supplied by a combustion of liquid or gaseous fuel.

Generally stated, the object of my invention is to provide a novel and improved construction whereby a furnace of this kind 15 may be operated more conveniently and with less expense than heretofore, and which will tend to reduce the cost of brass or other metals.

20 Another object is to provide a novel and improved furnace of this kind in which the receptacle in which the metals are melted can be tilted about a horizontally disposed axis to discharge the molten metal.

25 Another object is to provide a novel and improved construction whereby, as the result of tapering the receptacle, the fire-proof lining thereof can be easily removed by simply turning the smaller end of the 30 receptacle upward, thereby permitting the lining to drop downward through the larger end of the receptacle.

Another object is to provide a novel and improved construction whereby the heat of 35 combustion is transmitted very rapidly to the fire-proof materials below the mass of metal, as well as to the top of the mass itself, so that the heat is distributed more evenly and in a manner to accelerate the melting of 40 the metal.

It is also an object to provide certain details and features of construction and combinations tending to increase the general efficiency and desirability of a melting 45 furnace of this particular character.

To the foregoing and other useful ends, my invention consists in matters hereinafter set forth and claimed.

50 In the accompanying drawings:— Figure 1 is a side elevation of a furnace for melting brass or other metals, embodying the principles of my invention, certain

portions thereof being shown in section to illustrate the construction thereof.

Fig. 2 is a plan view of the right-hand 55 end portion of the structure shown in Fig. 1.

Fig. 3 is a vertical transverse section on line 3—3 in Fig. 1.

As thus illustrated, my invention comprises a horizontally disposed receptacle A, 60 which is known as the drum, and which is tapered from the point *a* in the length thereof to its left-hand end which is closed by a head B provided with a trunnion-bearing *b* by which it is supported for oscillating 65 movement about a horizontal axis. This receptacle is straight, preferably, from the point *a* to the head C at the smaller end of the receptacle, which head is preferably in the form of a casting provided with teeth 70 *c* which, in effect, form a bevel-gear. The bearing *b* is supported by an upright standard D, which may be a casting, and a similar standard or casting E is provided at the other end. The standard E is provided with 75 rollers F mounted to rotate about horizontal axes, and these rollers engage the periphery *f* of the head C, whereby the receptacle may be turned or oscillated about said axis. A short spindle G is mounted in a suitable 80 support *g* on an arm H which rises from the support or standard E, and this spindle is provided with a loose bevel-pinion I which engages the bevel-gear *e* so that rotation of 85 said pinion will oscillate or rotate the drum or receptacle. For this purpose, a hand-wheel J is loosely mounted on the outer end of the spindle G and suitably connected to said pinion, and by turning this hand-wheel 90 the pinion I can be rotated and the drum or receptacle will be tilted over in either direction. Near its larger end, said receptacle is provided at the top thereof with an opening K through which the products of combustion are exhausted, and through which the 95 metal is introduced into the receptacle and afterward discharged therefrom. The interior of the receptacle or drum is lined with tapered rings *k*, made of fire-clay or other suitable heat-resisting material. The receptacle or drum A itself can be of heavy 100 sheet-metal, or of any suitable material. Preferably, the head C is provided centrally with an orifice L, and a burner M, of any

suitable, known or approved character, is arranged in position to blow a flame through this orifice L and into the interior of the receptacle. Said burner is preferably of the kind which employs air-pressure supplied through a pipe N to the plug-valve *n*, and from the latter to the tapered nozzle *m*, and in which fuel oil is supplied through a pipe O to a valve *o*, and from the latter to an inner nozzle P, so that the oil is vaporized and mixed with the air, and the flame thus produced is blown into the end of the receptacle at the smaller end of the latter and in a direction toward the larger end thereof. 10 As stated, though, any suitable form of burner can be employed, which will produce a flame or blast of sufficient intensity to melt the metal.

In practice, the metal to be melted is introduced into the receptacle or drum A through the opening K, and is allowed to rest upon the fire-clay lining *k* at the bottom of the receptacle. The burner is then started, and when the flame or blast has been brought up to the proper intensity, the maximum combustion and greatest intensity of the heat are within the straight portion Q of the receptacle, the lining of which portion is not covered by the metal. The fire-proof lining becomes highly heated, and the heat is communicated rapidly from one ring *k* to another, so that the heat thus generated works or creeps under the metal, whereby the latter is subjected to heat from below as well as from above. The heat of the flame is directed forward against the mass of metal, and the products of combustion are blown forward against the metal and then upward and out through the opening K, so that the metal becomes highly heated; but, at the same time, as stated, the intense heat generated at the smaller end of the receptacle or drum is conducted through the fire-proof lining to the bottom of the mass of metal, so that the heat is more evenly distributed, causing the metal to melt uniformly and in the required manner. The rings *q* which form the lining of the straight portion Q are, it will be understood, of the same material as the rings *k*, and are substantially like the latter except that they are straight instead of being tapered. These rings do not need to be fastened to the drum or receptacle, but are simply arranged tight together and held in position by the support which they afford each other, and by reason of the fact that they are each preferably wide enough to prevent them from tilting over sidewise. In addition, the heads B and C can press against the rings at the ends of the receptacle, and this will tend to keep the rings all tightly crowded together.

As soon as the metal is melted and in the proper or required condition, the hand-wheel 65 J can then be turned to tilt the drum or re-

ceptacle A in either direction, causing the molten metal to be discharged from the opening K. In this way, the pouring operation is facilitated and rendered very simple, and as much of the metal can be poured at one time as may be desired, inasmuch as the receptacle can be tilted back very readily into normal position, if such is desirable after a portion of the molten metal has been poured off or discharged. 75

The head B can be secured by bolts R to the ring *r* secured to the end of the drum or receptacle A, whereby this head can be readily removed when it is desired to remove any accumulations resulting from the melting process, and when it is desired to remove the lining of the receptacle. This can be done, after the head B is removed, by turning the receptacle with its smaller end upward, thus allowing the rings *k* and *q* to release themselves by their own weight, and to fall downward through the larger end of the receptacle. In other words, the tapered shape of the receptacle makes it possible to simply hang the receptacle up by 80 its smaller end and shake the lining out of it, thus facilitating the cleaning or repairing of the furnace.

Thus, the receptacle A is constructed at one end to provide a combustion-chamber 95 for the flame of the burner M and has its other end portion constructed to receive and discharge the substance to be melted. Preferably, the receptacle is tilted about a horizontally disposed axis in order to discharge 100 the molten mass from the opening provided in the top of the receptacle, and said receptacle is also preferably tapered or funnel-shaped, as shown and described, as this is found to be advantageous in various ways. 105

Obviously, however, the construction and mode of operation may be changed or varied without departing from the spirit of my invention, and I do not limit myself to the exact construction shown and described. 110

What I claim as my invention is:—

1. In a melting furnace, a horizontally disposed, drum-shaped receptacle, axially rotatable, comprising a body tapering from its closed end toward its burner end, the portion adjacent said burner end being cylindrical, means whereby said closed end may be removed to open the receptacle, and a lining of heat-resisting and heat-conducting material laid in parallel, ring-shaped sections, to facilitate the removal of the lining when the closed end is removed and the drum turned to vertical position, the cylindrical end portion of the drum providing a combustion chamber from which the heat is conducted by said lining underneath the metal resting on said sloping bottom. 115 120 125

2. A structure as specified in claim 1, said drum having an opening in the tapered portion to receive the metal and through which 130

the molten mass is poured off after the metal is melted, and the lining rings in said tapered portion being tapered to fit the interior thereof, with one or more of said rings recessed to provide said lining with an opening opposite said opening in the drum.

3. A structure as specified in claim 1, a trunnion on said removable end to form the

longitudinal axis of rotation, said removable end being adapted to crowd the rings tightly together, and means at the burner end to rotate said receptacle.

Signed by me at Chicago, Illinois, this 27th day of November, 1916.

ALFRED FISHER.
